UNITED STATES PATENT OFFICE.

ADOLPH G. KUPETZ, OF NEW ROCHELLE, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed October 28, 1922. Serial No. 597,437.

To all whom it may concern:

Be it known that I, ADOLPH G. KUPETZ, a citizen of the United States, residing in New Rochelle, in the county of Westchester 5 and State of New York, have invented certain new and useful Improvements in Typewriting Machines, of which the following is a specification.

This invention relates to typewriting machines, and more particularly to typewriting machines for writing bills for telephone service, and is illustrated in the same type of machine as disclosed in my pending applications, Serial No. 592,682, filed October 6, 1922, and Serial No. 595,766, filed October 20, 1922. In making out these bills, it is required to type separately the amounts of United States taxes. It is desirable at the same time to keep track of the totals 20 of the tax items for a day or other long period. This has been done in the machines referred to by providing special "5" and "10" keys to be used for no other purpose than the writing of the tax items, and by 25 providing registers of the type of the well-known Veeder cyclometer for separately counting the operations of the special type-keys.

The machines referred to are characterized by the provision of spring means for advancing the operating arms of the registers to count and for maintaining the operating arms normally at the advance limits of their movements. This new normal position 30 of the register-operating arms results in the registers being maintained normally in a locked condition, which makes it necessary to retract the operating arm of a register in order to enable the register-clearing 35 mechanism to be operated. A partial retraction of the operating arm through a distance less than that required to cause an operation of the register is sufficient to unlock the wheels and permit their being turned by the clearing mechanism. Unless means are 40 provided, however, for controlling the distance through which the operating arm may be moved for this purpose, the operator, in attempting to cause such a partial retraction, 45 is apt to move the operating arm too far, and to cause the clearing operation to be followed by a counting operation, thus running a unit into the wheels. On the other hand, a full retraction of the operating arm, 50 such as is effected by the depression of the

number-key, while certain in its effect, necessitates the provision of means for arresting the clearing operation with the number-wheels standing at "9", in order that the ensuing counting operation which occurs upon the restoration of the parts to normal position may advance the wheels to "0". The principal feature of this invention is the provision of supplemental means, 60 in a machine of the character referred to, for partially retracting the register-operating arm independently of the number-key to unlock the register and for limiting the extent of the retracting movement, so as to 65 positively insure that the register will not be operated on the return of the arm to its normal position, and hence provides a simple and effective means whereby the number-wheels may be cleared directly to "0" 70 and independent of the return movement of the operating arm to relock the wheels. Thus the operating arm is subject to a full operative stroke between fixed stop positions by the number-key and a partial inoperative stroke by the supplemental means 75 for clearing purposes.

Other features and advantages will hereinafter appear.

In the accompanying drawings, 80 Figure 1 is a sectional side elevation of the front portion of a typewriting machine having the present improvements applied thereto.

Figure 2 is a plan view of the front right-hand portion of the machine. 90

Figure 3 is a sectional view of a register on the line 3—3 of Figure 2, showing the parts in their normal positions.

Figure 4 is a view, similar to Figure 3, showing the parts in the positions to which 95 they are moved to unlock the number-wheels in a clearing operation.

Figure 5 is a vertical sectional view of the register, showing the arrangement of the operating and clearing shafts. 100

The typewriting machine comprises number-keys 11, alphabet-keys 12, and key-levers 13 operated by the keys to cause types 14 to print in the usual manner. Special keys are provided to be used exclusively for writing the tax items, one such key for writing the number "5" being shown at 5. A bracket 15, which may be clamped to the frame 16 of the machine by screws 17 and a clamping plate 18, supports a register 19 for counting the 110

operations of the special "5" key. Although only one special key and one register are shown, it will be understood, of course, that the invention is not limited in scope to use 5 with a single special key and a single register. A rock-shaft 20, journaled in the lower portion of the bracket 15, has a crank-arm 21 underlying the special "5" key in proximity to the stem 22 thereof and a 10 second crank-arm 23 which has a pin-and-slot connection with the operating arm 24 of the register 19. A spring 25, connected to the tail of the register-operating arm 24 and to the bracket 15, normally maintains 15 the operating arm 24 at the advance limit of its movement. The depression of the special "5" key retracts the operating arm 24 to prepare the register for an operation, and the spring 25 advances the operating 20 arm to effect the operation.

The register 19 may be conveniently an ordinary Veeder cyclometer. The register-operating arm 24 is fixed to an operating rock-shaft 26, which carries and oscillates 25 a yoke 27. A series of pawls 28 is pivotally mounted on this yoke and is spring-pressed toward number-wheels 29 for co-operation with ratchet-teeth 30 on the number-wheels and with intervening shallow and deep 30 notches 31 and 32 in the usual way. A hub-portion 33 of the yoke 27 operates a gear-segment 34 to swing stops 35 into and out of engagement with the ratchet-teeth 30 on the number-wheels 29 to prevent overthrow of 35 the number-wheels and to lock them against advance in the normal position of the parts, which is the position in which they are shown in Figure 3. Spring-pressed pawls 36 lock the number-wheels 29 against retrograde movement. A clearing handle 37 is provided, for turning a clearing shaft 38 having a series of one-toothed cams 39 fixed upon it, one cam for each of the number-wheels 29. Each number-wheel carries a pawl 40 and a spring 41 which presses the pawl into engagement with its cam 39 on the clearing shaft.

For the purpose of unlocking the number-wheels 29 by a partial retraction of the operating arm 24, a supplemental unlocking handle or lever 42 is rotatably mounted on the operating shaft 26, and is provided with a lug 43 extending laterally to overlie and engage the register-operating arm 24. This handle 42 has a tail 42^a which, by engagement with a pin 44 on the register-frame 45, limits the depression of the unlocking handle. When the operating arm 24 is actuated by the number-key 5 in the ordinary operation 50 of the machine, the unlocking handle 42 remains immovable, a cup-spring 46 mounted on the register-operating shaft 26, between the unlocking handle and the register-frame 45, exerting a light frictional pressure 55 against the handle 42 to retain it in its ele-

vated position. When it is desired to clear the register 19, the operator depresses the unlocking handle 42 as far as the stop-pin 44 will permit. This moves the parts to the position shown in Figure 4, in which position it will be noticed that the stops 35 are swung clear of the number-wheels 29, although the number-wheel-operating pawls 28 are retracted less than a tooth-space of the number-wheels. The register-clearing 70 handle 37 is then turned, causing the clearing shaft 38 and the cams 39 upon it to turn in a counterclockwise direction, as seen in Figure 3. The teeth 39^a of the cams 39 pick up the pawls 40 on the number-wheels 29 in 75 the positions to which they have been moved in the preceding counting operations, and turn the number-wheels. When the number-wheels have been moved to "0," the turning 80 of the clearing handle is discontinued and the unlocking handle 42 is released. The spring 25 immediately restores the register-operating arm 24 and the unlocking handle 42 idly to their normal elevated positions.

Variations may be resorted to within the 85 scope of the invention, and portions of the improvements may be used without others.

Having thus described my invention, I claim:

1. In a typewriting machine, a number-key, a register for counting the operations of the number-key, means normally maintaining the register in locked condition to prevent clearing thereof, the register comprising register-clearing mechanism, means for unlocking the register to permit operation of the register-clearing mechanism, and supplemental means for insuring that no counting operation of the register will ensue as a result of the operation of the 105 unlocking means.

2. In a typewriting machine, a number-key, a register for counting the operations of the number-key, normally maintained in a locked condition, comprising clearing mechanism, register-operating means movable to unlock the register, and supplemental means for moving the register-operating means a mechanically limited distance to unlock the register, to permit the register 110 to be cleared, without causing a counting operation thereof.

3. In a typewriting machine, a number-key, a register for counting the operations of the number-key, normally maintained 115 in a locked condition, comprising clearing mechanism, register-operating means movable to effect counting operations of the register, and an unlocking handle for moving the register-operating means through a distance less than that necessary to cause a counting operation to be effected.

4. In a typewriting machine, a number-key, a register for counting the operations of the number-key, normally maintained 120

in a locked condition, comprising clearing mechanism, a register-operating arm movable in one direction to a fixed stop position to prepare the register for operation, and 5 movable in the other direction to operate the register and supplemental means for moving the arm a distance insufficient to prepare the register for an operation but sufficient to unlock the register for clearing 10 purposes.

5. In a typewriting machine, a number-key, a register for counting the operations of the number-key, normally maintained in a locked condition, comprising register-clearing mechanism, a register-operating arm movable to unlock the register and to cause the register to be operated, an unlocking handle for moving the register-operating arm to unlock the register, and means 20 for arresting the movement of the unlocking handle when the operating arm has been moved a distance sufficient to unlock the register but insufficient to cause a counting operation thereof.

25 6. In a typewriting machine, a number-key, a register operated by the number-key normally maintained in a locked condition, a register-operating arm movable to unlock the register and to cause the register to be operated, unlocking means for moving the register-operating arm to unlock the register, and means for controlling the distance the operating arm may be moved in said 30 unlocking movement.

35 7. In a typewriting machine, a number-key, a register operated by the number-key normally maintained in a locked condition, a register-operating arm movable between fixed stop positions to unlock the register 40 and to cause the register to be operated, and supplemental unlocking means for moving the register-operating arm to an intermediate position to unlock the register independently of the number-key for clearing 45 purposes.

8. In a typewriting machine, a number-key, a register, clearing mechanism therefor, a register-operating arm arranged to be vibrated between fixed stop positions by 50 the depression of the number-key, a spring for returning the register-operating arm to normal position, and supplemental means for partially retracting the register-operating arm independently of the number-key 55 for clearing purposes.

9. In a typewriting machine, a number-key, a normally-locked register comprising clearing mechanism, a reciprocable register-operating arm, connections between the 60 number-key and the register-operating arm for fully depressing the operating arm to prepare the register for counting, said operating arm being effective in the initial portion of its depression to unlock the register, a lever engaging the operating arm for 65

depressing it, and a stop for limiting the range of movement of the lever.

10. In combination, a register comprising clearing mechanism, a register-operating handle, a spring for maintaining the operating handle normally at the advance limit of its movement to maintain the register in a locked condition and for advancing the operating arm to effect a counting operation after each full retraction of the operating arm, and means for causing a partial retraction of the operating arm of predetermined extent to unlock the register so as to permit the operation of the clearing mechanism. 70

11. In a typewriting machine, a number-key, mechanism for counting the operations of the number-key, comprising number-wheels having ratchet-teeth thereon and reciprocable pawls for advancing the number-wheels in counting, an operating arm arranged to advance and retract the pawls, a spring for actuating the operating arm to advance the pawls, and to maintain them normally at the advance limits of their movements, connections between the operating arm and the number-key for operation by the number-key to retract the pawls a ratchet-tooth-space when the number-key is depressed in writing, wheel-clearing mechanism, means controlled by the operating arm to lock the number-wheels in the latter portion of the advance of the operating arm, and supplemental means for retracting the operating arm a distance sufficient to unlock the number-wheels for clearing purposes. 80

12. In a typewriting machine, a number-key, a register for counting the operations of the number-key, comprising number-wheels, number-wheel-advancing mechanism, number-wheel-locking mechanism controlled by the advancing mechanism to lock the number-wheels in the latter portion of the advance, clearing mechanism, supplemental means for retracting the number-wheel-advancing mechanism a limited distance to unlock the register, and means for automatically restoring the advancing mechanism to its advance limit of movement to cause the register to be unlocked at "0". 95

13. In a machine of the class described, 105 a register comprising a series of number-wheels with individual locking means, a clearing mechanism for the wheels, a register-operating arm having a uniform full-stroke movement to release the locking means and register an operation, and supplemental means to unlock the wheels without registering, for clearing purposes. 115

14. In a typewriting machine, a frame, a number-key, a removable bracket secured to 125 the frame for supporting said register, register-operating means carried by the bracket for operation by the number-key but unconnected thereto, and means having a limited range of movement to partially actuate the 130

- register-operating means to unlock the number-wheel and permit the register to be cleared.
15. In a machine of the class described, a register comprising a series of number-wheels and a clearing mechanism, an arm for operating the register to count, and a lever supplemental to the arm to condition the register without counting, for clearing purposes.
16. In a machine of the class described, a counting register comprising a series of number-wheels and a means to clear the wheels to "0", an arm for operating the register having a uniform movement between fixed stops, and a lever supplemental to the operating arm to prevent registry of the latter and condition the wheels for clearing them to "0".
17. In a machine of the class described, a counting register comprising a series of number-wheels, individual wheel-locking means and a wheel-clearing mechanism, an arm for operating the register that vibrates between fixed stops, and a supplemental lever to vibrate said arm to an intermediate position between the stops to unlock the wheels and render the clearing mechanism operative to restore the wheels to "0".
18. In a machine of the class described, a register comprising a series of number-wheels and a wheel-clearing mechanism, a series of pawls for driving individual wheels, a carrier for the pawls arranged to vibrate between fixed stops to register, an arm to vibrate the carrier, and means supplemental to said arm whereby the carrier and pawls may be vibrated to an inoperative position between the stops and render the clearing mechanism effective to restore the wheels to "0".
19. In a machine of the class described, a register comprising a series of number-wheels and a register-clearing mechanism, interlocks to prevent movement of the wheels in either direction at normal position, individual pawls to drive each wheel forwardly to register, a carrier for all the pawls to swing between fixed stops at each registering movement, an arm to operate the carrier for a full stroke at each movement, and a lever supplemental to the arm whereby the arm will unlock the wheels and vibrate the carrier and pawls to an inoperative position between the stops and condition the wheels to co-operate with the register-clearing mechanism to restore the register to "0".

ADOLPH G. KUPETZ.
